UNITED STATES PATENT OFFICE.

NILS D. LEVIN, OF COLUMBUS, OHIO, ASSIGNOR TO THE JEFFREY MANUFACTURING COMPANY, OF COLUMBUS, OHIO, A CORPORATION OF OHIO.

MINING-MACHINE.

1,895,647.

Specification of Letters Patent.

Patented Nov. 1, 1921.

Application filed September 28, 1916, Serial No. 122,705. Renewed January 28, 1921. Serial No. 440,802.

To all whom it may concern:

Be it known that I, NILS D. LEVIN, a citizen of the United States, residing at Columbus, in the county of Franklin and the State of Ohio, have invented certain new and useful Improvements in Mining-Machines, of which the following is a specification, reference being had therein to the accompanying drawing.

10 The present invention relates to certain new and useful improvements in mining machines, and especially to that class of mining machines wherein each machine is provided with an elongated cutting mechanism adapted to be thrust longitudinally into the coal, and to then be moved laterally across the working face to form a kerf to facilitate the breaking out of the coal.

In many regions there occur veins of coal 20 which, while very thin and difficult of recovery, may be profitably mined owing to the high cost of other fuel with which they come into competition. Where the character of the overlying strata will admit of its practice, the long wall system is best suited to, and is commonly employed in the recovery of coal from very thin veins, and mining machines adapted to cut across the working faces of the long wall system have been developed wherein the overall height of the machine has been reduced to the lowest practical limit. There are, however, territories underlain by such veins of coal where the nature of the roof is not suitable to long wall mining and recourse must be had to the room and pillar system.

It is the especial object of this invention to provide a mining machine of suitable strength and ample power, having vertical 40 dimensions suitable to use in extremely low coal and adapted to be operable under the conditions obtaining with the relatively short working faces of the room and pillar system of mining, or in the limited space available between the roof supporting props and the working face in the long wall system.

A further object is to provide improved feeding mechanism whereby the machine 50 may be moved at a relatively slow speed for cutting the coal and at a relatively high speed for handling about the room.

A further object is to provide improved mechanism for connecting the motor of the 55 mining machine with the axles of a suitable

truck to transport the machine about the mine.

These and other objects will appear in the following specification, reference being had to the accompanying drawings of which: 60

Figure 1 is an elevation of the right hand side of the preferred embodiment of my invention, mounted upon its truck for transportation along the mine tracks.

Fig. 2 is a general plan view of the machine illustrated in Fig. 1.

Fig. 3 is a fragmentary enlarged plan view with some parts broken away to show other parts of the driving mechanism for the devices by which the machine is moved relative to the coal face.

Fig. 4 is a section along the line 4-4 of Fig. 3.

Fig. 5 is a section along the line 5-5 of Fig. 2 slightly distorted as to the plan of the section.

Fig. 6 is a section along the line 6-6 of Fig. 2.

Fig. 7 is a section along the line 7-7 of Fig. 2.

Fig. 8 is a section along the line 8-8 of Fig. 2.

Fig. 9 is a fragmentary elevation showing the retarding devices and truck drive on an enlarged scale.

Fig. 10 is an elevation of the left hand side of the machine.

Fig. 11 is a rear elevation of the machine.

Fig. 12 is a fragmentary plan view showing the method of loading the machine upon its truck for transport about the tracks of the mine.

Fig. 13 is a detail of the removable guide sheave.

Figs. 14 to 18 inclusive are diagrams 85 showing the methods of using the machine.

Like numerals refer to similar parts in the several figures.

As shown in the drawings this machine comprises a main frame composed of three 100 steel castings indicated by the numerals 1, 2 and 3. These castings are securely attached together by the bolts 4 and are shaped below to form the broad base 5 upon which the machine rests and which is adapted to slide 105 over the floor of the mine. The rear casting 1 supports and incloses the feeding mechanism and the parts associated therewith. The middle section 2 is shaped to form the motor frame which entirely incloses the 110

- armature 6, field poles 7 and the accessory parts of the motor, and contains a chamber for the protection and support of the starting box 8 by which the motor is controlled.
- 5 The operating shaft 8^a of the starting box 8 extends longitudinally of the machine, and at either end is provided with hand wheels 8^b convenient to the hand of the operator, by which the starting box may be manipulated.
- 10 The forward casting 3 carries the cutting mechanism and the gearing by which it is actuated from the motor.

The cutting mechanism is of the well known side cutting type consisting of an 15 elongated frame 9 having guideways along its edges in which travels the cutter chain 10. To the links of the chain 10 are attached the renewable bits 11 by which the coal is cut. This elongated frame 9 is secured by 20 any suitable means, as by the bolts 12 to a support casting 13 having a circular expansion 14 at the center of which is a journal bearing which engages the hub 15 of the frame casting 3. Secured to the upper side 25 of the circular expansion 14 is a ring 16 in engagement with the flange 17 of a bearing ring 18 attached to the casting 3 forming a turntable upon which the cutter arm 9 is supported and guided for rotation in a horizontal plane about the axis of the hub 15. Formed in the casting 3 is an aperture 19 through which may be extended a coupling pin 20 to engage a suitable aperture in the 30 ring 18 to lock the cutter arm 9 in the desired position during the operation of the machine.

By this method of mounting the cutter arm, the machine is adapted to use in either the long wall or the shaft wall systems of mining, and the cutter arm may easily be rotated to either side to facilitate the passage of the machine around the short curves in the narrow passages of the mine. Mounted 40 for rotation in the journal bearings 21 formed in the hub 15 is a vertical shaft 22 and to the lower end of this shaft is fixed the sprocket wheel 23 which engages the cutter chain 10 to drive it. Fixed to the upper end of this shaft 22 is a worm wheel 24 having a hub 45 25 the outer surface of which is finished to form a journal rotatable in the bearing 26 formed in the hub 27 of the casting 28. This casting 28 is secured by suitable bolts to the frame casting 3 and forms the cover part of 50 the gear case by which the worm wheel and its associated parts are protected. The lower part of the gear case is formed by the web 29 of the frame casting 3 and these parts are so shaped and proportioned that they may 55 hold a supply of oil to such depth that the rim of the worm and worm wheel will dip therein to insure proper lubrication.

The worm wheel 24 is the cutter driver and is engaged by a worm 30 which is formed 60 integral with the shaft 31 which extends lon-

gitudinally of the machine and is supported in suitable ball bearings 32 in the frame casting 3. Rotatable upon the shaft 31 is a spur gear 33 which engages with the pinion 34 attached to the armature 6 of the motor. 70 This spur gear 33 is provided with a sleeve 35 extending through the ball bearing 32 and having on its outer end clutch teeth 36 which are adapted to engage with the teeth of a clutch member 37 splined on the shaft 75 31. The clutch member has an annular flange 38 which engages with the shifting yoke 39. The yoke 39 is fixed to a vertical shaft 40 to the upper end of which is attached a crank arm 41. To the crank arm 80 41 is connected a shifting rod 42 which extends longitudinally of the machine to a point convenient to the hand of the operator. By the manipulation of this rod 42 the clutch member 37 may be moved longitudinally on 85 the shaft 31 to engage or disengage the teeth 36 of the gear 33 as it may be desired to drive the cutter chain 10 or to allow it to remain idle. An annular groove 43 is formed on the end of the circular expansion 14 to engage 90 the feed rope during the sumping cut when the machine is used in the long wall system of mining as will be fully set forth hereinafter. A transverse bar 44, the ends 45 of which are bent rearwardly and attached to 95 the frame casting 3, is adapted to engage the face of the coal when the machine is used in the room and pillar system of mining, to protect the operative parts of the machine from contact with the coal.

100 The feeding mechanism by which the machine is moved relative to the coal comprises a rope adapted to be attached at one end to an abutment outside the machine and at the other end to a winding drum 47 mounted 105 within the rear section 1 of the machine frame in such manner that by the rotation of the drum the rope will be wound up to drag the machine over the floor of the mine. The drum 47 is adapted to be rotated at a 110 relatively high speed to move the machine into position to begin its cutting, or to load it upon the truck after the completion of a cut.

Attached to the rear end of the armature shaft 6 of the motor is a worm 48 which engages a worm wheel 49 fixed to the hub of a bevel gear 50. The bevel gear 50 is keyed to a vertical shaft 51 journaled in the bearings 52 and 53 of the gear case castings 54 and 55 which are suitably secured to the 115 frame casting 1. In order that the gears 48, 49, 50 and 93 may at all times be immersed in oil, the gear case 54-55 is provided with the packing glands 54^a and 54^b and with the plug cap 54^c to prevent the escape of oil from the interior of the gear case. Formed integral with the shaft 51 at its upper end is a crank 56 having a crank pin 57 to which is connected the connecting rod 58. This connecting rod 58 is formed 120 125 130

in two parts which are screw threaded together to admit of adjustment of the length of the rod, and is provided with a lock nut 59 to prevent accidental change of such adjustment. At its end remote from the crank 56 the connecting rod 58 is connected by the wrist pin 60 to two rocker arms 61 which are rotatable about a sleeve 62 journaled upon the vertical shaft 63. This shaft 10 63 is secured at its lower end to the frame casting 1 and at its upper end to the yoke casting 64 which is bolted to the frame of the machine. Keyed to the sleeve 62, between the rocker arms 61, is a ratchet wheel 65 adapted to be engaged by the pawl 66, carried by the rocker arm 61, by which the ratchet wheel and with it the sleeve 62, may be rotated. A pawl 67 carried by the yoke casting 64 also engages the ratchet wheel 20 65 to prevent its retrograde rotation. Formed on the lower end of the sleeve 62 are gear teeth 68 which constitute a pinion in engagement with the gear wheel 69 to cause it to rotate about the vertical shaft 25 70. The ends of the shaft 70 are secured in apertures of the frame and yoke castings to hold it firmly in place. The gear wheel 69 is provided with an elongated hub 71 within which are formed bearings 72 rotatable upon the vertical shaft 70 and upon the outer surface of this hub 71 the drum 47 is mounted for free rotation. In the web 73 of the gear 69 is formed a truncated cone 74 the upper surface of which is adapted to 30 engage a complementary surface formed in the inside of the drum 47 constituting a friction clutch by which the drum may be rotatively connected to the gear 69. Attached to the flanges 75 of the drum is a ring 76 which bears upon an annular flange 77 formed on a nut 78 screw threaded to the upper part of the hub 71. This hub when in the upper position of its adjustment supports the weight of the drum and holds it 45 out of engagement with the clutch cone 74 and when in its lower position allows the cone surfaces to engage, and by pressing upon the upper end of the drum casting, holds them in forcible contact to drive the drum. Formed on the nut 78 are radial arms 79 by which it may be rotated relative to the hub 71 to change the vertical relation of the clutch members. Below the bottom flange 50 80 of the drum 47 is a cylindrical extension 81 which protrudes through a circular aperture in the cover plate 82 which is attached to the frame of the machine to protect the gearing of the feeding mechanism. Attached to the cover plate 82 by suitable machine screws is a packing ring 83 which contacts with the cylindrical extension 81 to maintain a dust proof joint irrespective of the vertical position of the drum 47. Rotatable about the sleeve 62, at either 55 60 side of the ratchet wheel 65 are arms 84 to

which are attached an arcuate shield 85 partially encircling the ratchet wheel, and having an aperture through which the pawl 66 extends to engage the teeth of the ratchet wheel. By the rotation of these arms 84 the 70 shield 85 may be moved to engage the pawl 66 to prevent its engagement of the ratchet wheel through a greater or less part of its rotation. A rod 86 extending longitudinally of the machine, is connected to the arms 75 84 by the link 87 and the longitudinal movement of this rod rotates the arms 84 to vary the position of the shield 85. The ends of the rod 86 are convenient to the hand of the operator at either end of the machine 80 and afford convenient means for regulating the rate of winding the feed rope and consequently the rate of feeding the machine into the coal.

By the arrangement of parts just above 85 described power from the motor may be connected to the winding drum 47 to wind the feed rope 45 to feed the cutting mechanism into the coal, and the rate of such feeding may be controlled by the operator 90 within the range of practical needs. It is found, however, that a rate of winding which is suitable for feeding the cutting mechanism into the coal is entirely too slow for handling the machine about the room, preparatory to beginning a cut, or to load it onto its truck for transport to another working place. I have therefore provided auxiliary gearing by which the drum may be rotated at a much higher rate when handling 95 the machine about the room.

Mounted upon the horizontal shaft 90, which is journaled in suitable bearings 91 of the gear case casting 54 is a bevel pinion 93 engaging the bevel gear 50. To the opposite end of the shaft 90 is fixed a spur gear 94 which engages the spur gear 95 keyed to the shaft 96. The gear 95 is formed with a sleeve 97 on the outer surface of which is formed a journal rotatable in the bearings 98 of the gear case 99. A flange 100 formed on the inner end of the sleeve 97 engages the face of the bearing 98 to prevent longitudinal movement of the shaft 96 and gear 95. A sleeve 101 keyed to the shaft 115 86 remote from the sleeve 97, forms a second journal to support the shaft 86 in the bearing 102 of the gear case casting. Slidable longitudinally of the shaft 96, and connected rotatively therewith by a suitable 120 key 103, is a worm 104 adapted when in one position to engage, and when in another position to be disengaged from the worm wheel 105 which is fixed to the ratchet sleeve 62. When the worm 104 engages the worm wheel 125 105 power from the motor is transmitted through the above described train of gears to rotate the sleeve 97 and through it the drum 47 at a relatively high speed, the pawl 66 trailing idly over the teeth of the ratchet 130

wheel 65. Formed on the hub of the worm 104 is an annular flange 106 which is engaged by the shifting arm 107 attached to the vertical shaft 108 journaled in suitable bearings 109 of the gear case casting. The shaft 108 is provided with a crank arm 110 by which it may be rotated to shift the worm 104 along the shaft 96, and this crank arm is connected with a rod 111 which extends 10 to a point convenient to the hand of the operator. A lug 112 attached to the rod 111 is adapted to engage the web 113 of the frame casting 1 to prevent accidental shifting of the worm into its engagement with 15 the worm wheel. When the worm 104 is in engagement with the worm wheel 105 its thrust is in the direction of, and is carried by the face of the bearing 102 of the gear case, and tends to maintain such engagement.

Securely bolted to the frame casting 1, is a supporting casting 115 upon which is mounted the retarding device by which the outer end of the machine is guided when 25 used in the room and pillar system of mining, as will be fully explained hereinafter. From this support casting 115 projects a horizontal stud shaft 116 and upon this is journaled the double flange drum 117 upon 30 which the retarding rope 118 may be wound. The drum 117 is extended beyond the flange 119 to form a brake drum 120 which is adapted to be engaged by the friction brake band 121 attached to the support casting 35 115 at 122. An adjusting bolt 123 having a nut 124 affords convenient means to vary the tension of the brake band 121 to adjust the resistance to the rotation of the drum 117 when there is a strain on the rope 118. 40 Suitable guide sheaves 125 and 126 are mounted upon the support casting 115 by which the rope 118 may be lead from the drum 117 toward either side of the machine. Mounted upon suitable spindles attached 45 to the frame casting 1 are the sheaves 127, 128 and 129 over which the feed rope 46 may be guided in the desired direction to feed the machine. A sheave 130 is also provided to be convenient for guiding the feed 50 rope 46 when handling the machine. Attached to the bar 45 at either side of the machine is a sheave support 131 upon which is mounted a sheave 131^a, adapted to be used to guide the feed rope from the machine 55 to an anchor adjacent the coal face at either side of the machine as the direction of cutting may require.

In the long wall system of mining the working faces are commonly several hundred 60 feet long with an entry at each end, into which the cutting mechanism may project when beginning the cut and across which the body of the mining machine may project while finishing such cut. When working 65 under such conditions as shown in Fig.

14 the frame of the machine extends along the face of the coal with the feeding mechanism forward. The cutter arm extends laterally of the frame, into the coal, its inner end somewhat in advance of the outer end, 70 so as to form an acute angle with the machine frame. The feed rope 46 is drawn out from the drum 47, passed around the guide sheave 127 and attached to a suitable anchor 132 in advance of the machine adjacent the coal face. It has been found that, with the above arrangement of parts, the reaction of the cutting bits 11 tends to draw the machine toward the face of the coal, and will hold it to its work without other guiding devices.

Should there be no free end to the coal face at the point where it is desired to begin the cutting operation the machine may be placed adjacent the coal face with the cutter 85 arm extending rearwardly parallel thereto as illustrated by the dotted lines at 10^a in Fig. 17 of the drawings. After starting the cutting mechanism the cutter arm may be rotated to the desired angular position indicated by the full lines at 10 of Fig. 17, thus making the sumping or entering cut, after which the operation will proceed as above described.

When operating upon the relatively short 95 walls of the room and pillar system of mining, it is necessary for the cutting mechanism to work close up to the rib at each side of the room. This necessitates a somewhat different method of handling the machine, wherein the frame of the machine extends outward into the room at right angles to the coal face, as illustrated in Figs. 15 and 16. When the machine has been brought into the room, unloaded from its 100 truck, and moved across the floor of the mine to the right hand side of the room with the end of the cutter arm in the angle formed by the face and rib the feed rope 46 will be drawn out from the drum 47, passed 110 around the guide sheaves 128, 129 and 131^a, and its end connected to the anchor jack 133 placed near the face of the coal. As the strain on the feed rope 46 tends to swing the outer end of the machine to the right, 115 the retarding rope 118 will be drawn out from the drum 117 and connected to the anchor jack 134 suitably placed at the left hand side of the machine. When now the cutting mechanism is started and the feed 120 rope is wound up the machine will be drawn longitudinally toward the coal face to force the cutter arm into the coal to form the entering, or sumping cut. After the completion of the sumping cut the jack 135 will 125 be placed at the left hand side of the room near the face. The rope 46 will be passed around the sheaves 127 and 131^a and its end connected to this jack 135. When now the feed rope is wound the machine will be 130

drawn across the room to cut the coal. The resistance of the coal to the passage of the cutting mechanism tends to cause the outer end of the frame to swing to the left. To overcome this tendency the jack 136 is placed at the right hand side of the room and the retarding rope 118 connected thereto. The nut 124 is then manipulated to adjust the tension of the brake band 121 to resist the unwinding of the rope 118 thereby holding the machine in the desired angular relation to the face of the coal.

In Fig. 18 is illustrated a method of forming the sumping or entering cut at the angle formed by the working face and the rib when the clear space in front of the working face is not sufficient to allow the frame of the mining machine to extend outwardly longitudinally of the cutting mechanism. As here illustrated the machine is placed diagonally adjacent the coal face with the cutter arm locked at right angles and extending into the corner of the working place. The retarding rope 118 is attached to a jack 157 placed in advance of the machine near the working face and the feed rope 46 is carried around the guide sheave 131^a and attached to an anchor 158 placed in the angle formed by the rib and face. Upon winding the feed rope the machine will swing about the jack 157 as a pivot, drawing the cutter arm longitudinally into the coal to form the sumping cut as indicated by the dotted lines in Fig. 18. After the completion of the sumping cut the operation may be continued in the manner common in the long wall system.

It is obvious that many variations may be made in the method of operating this machine to meet the varying requirements in the coal mines but it is thought that the above illustrations are sufficient to demonstrate that the machine is capable of operation under any of the conditions met with in either the long wall or short wall systems of mining.

After the completion of the cut it will be desirable to remove the machine to another working place and for this purpose I have provided a truck adapted to conveniently load and unload the machine. This truck comprises two longitudinal side rails or skids 137 joined by suitable cross members of which the channel bar 138 is one. These skids are mounted upon the axles 139 and traction wheels 140, which are adapted to travel over the tracks of the mine. Rotatably and slidably mounted upon the shaft 96 is a sprocket wheel 141 having a hub 142 on the face of which is formed clutch teeth 143 adapted to engage similar teeth 144 formed on the sleeve 101. Formed on the hub 142 is an annular flange 145 adapted to be engaged by either side of the latch member 146 pivotally attached to the frame cast-

ing 1 to hold the clutch teeth 143 and 144 either in or out of engagement as it is desired to drive the sprocket wheel 141 or to allow it to remain idle. A driving chain 147 is adapted to connect the sprocket wheel 141 with a similar sprocket wheel fixed to the axle 139 to propel the truck. Mounted in suitable apertures of the cross member 138 is a rod 148 having at its forward end a hook 149 adapted to engage with the aperture 150 of the frame casting 1. Screw threaded to the rod 148 is a hand wheel 151 adapted to engage the cross member 138 and by its rotation to draw the rod 148 rearwardly of the truck. To load the machine the rear end of the skids 137 are lifted to depress the forward ends which are inserted below the frame of the machine. The feed rope is then drawn out passed around the sheave 128 of the mining machine, and the sheaves 152 and 153 mounted upon the cross member 138 of the truck, and its end attached to the hook 154 formed on the frame casting 1 of the mining machine. When now the rope is wound up the machine will be drawn onto the truck. When drawn sufficiently far for the hook 149 to engage the aperture 150 the driving chain 147 will be placed around the sprocket wheel 141 of the mining machine and around the sprocket wheel of the axle 139 and the hand wheel 151 rotated to draw the machine rearwardly to properly tension the chain 147. An adjustable stop is provided in the set screw 155 to prevent the machine being drawn so far as to strain the driving chain, and when the hand wheel 151 draws the machine tightly against this stop 155 it will be securely locked in position upon the truck.

What I claim is:

1. In a mining machine, the combination of a main frame adapted to rest upon and slide over the floor of a mine, of a horizontally extending elongated cutting mechanism pivotally supported on said main frame, means to rotate said cutting mechanism about its pivot during the cutting operation, means to lock the said cutting mechanism in any one of several angular relations relative to the main frame, means to move the machine bodily relative to the coal face, and means exclusive of said moving means mounted upon said main frame to control its angular relation with the coal face during either lateral or longitudinal movement of the cutting mechanism.

2. In a mining machine, the combination with a main frame adapted to rest upon and slide over the floor of a mine, of a horizontally extending elongated cutting mechanism pivotally supported on said main frame, means to lock said cutting mechanism in any one of several angular relations with the main frame, feeding mechanism adapted to move the cutting mechanism relative to

105

110

115

120

125

130

the main frame or to move the machine bodily relative to the material to be mined, and means exclusive of said feeding mechanism mounted upon said main frame to control 5 its angular relation with the material to be mined during either lateral or longitudinal movement of the cutting mechanism.

3. In a mining machine, the combination with a main frame adapted to rest upon and 10 slide over the floor of a mine, of a horizontally extending elongated cutting mechanism pivotally supported on said main frame, means to lock said cutting mechanism in any one of several angular relations 15 with the main frame, feeding mechanism comprising a winding drum and a flexible draft member adapted to move the cutting mechanism relative to the main frame or to move the machine bodily relative to the material to be mined, and mechanism comprising a winding drum, a draft member windable upon the drum, and means to resist the 20 unwinding of the draft member, adapted to preserve a balance of forces whereby the 25 machine will be guided either longitudinally or laterally of the cutting mechanism.

4. In a mining machine, the combination of an elongated substantially rectangular main frame adapted to travel with its side 30 parallel and close to the coal face, a motor on the frame having its armature shaft parallel with the longitudinal lines of the frame, a horizontally arranged cutter chain, an arm carrying said chain and mounted at 35 one end of said frame on a vertical axis in the central vertical longitudinal plane of the frame, a worm wheel on said axis for driving said cutter chain, a worm near the side lines of the frame on an axis parallel with 40 the armature shaft and engaging said worm wheel, gears connecting the armature shaft with the worm, the cutter arm being adapted to move across the vertical lines of the worm, a feed mechanism mounted on the 45 opposite end of the frame for moving the frame and the cutter comprising a second worm mounted upon the armature shaft at the other end of the motor, a worm wheel meshing with the said worm, a drum, a cable on 50 the drum, and power transmitting devices interposed between the worm wheel and the drum for rotating it to tension the cable.

5. In a mining machine, the combination 65 of a main frame adapted to rest upon and slide over the floor of the mine and constituting the magnetic field frame of an electric motor, an armature in the magnetic field frame having its longitudinal lines parallel 70 with the longitudinal lines of the main frame, a horizontally arranged cutter chain, an arm carrying said chain and mounted at one end of the frame on a vertical axis in the central vertical longitudinal plane 75 of the frame, a worm wheel on said axis for

driving the cutter chain, a worm near the side lines of the frame on an axis parallel with the axis of the armature and engaging with said worm wheel, gears connecting the armature with the worm, the cutter arm being adapted to move across the vertical lines of the worm, a feed mechanism mounted at the opposite end of the frame for moving the frame and the cutter comprising a second worm mounted upon the armature shaft 80 at the other end of the motor, a worm wheel meshing with said worm, a drum, a cable on said drum, and power transmitting devices interposed between the worm wheel and the drum for rotating it to tension the cable. 85

6. In a mining machine, the combination with a main frame adapted to rest upon and slide over the floor of a mine, of a horizontally extending elongated cutting mechanism pivotally supported on said main frame, means to lock said cutting mechanism in any one of several angular relations with the main frame, feeding mechanism adapted to move the cutting mechanism relative to the main frame or to move the machine 90 bodily relative to the material to be mined, and frictionally controlled devices adapted to maintain any preferred angular relation of the main frame to the material to be mined during the cutting operation. 95

7. In a mining machine, the combination of a main frame adapted to rest upon and slide over the floor of the mine, of a horizontally extending elongated cutting mechanism pivotally supported on said main frame, means to rotate said cutting mechanism about its pivot during cutting operation, means to lock said cutting mechanism in any one of several angular positions relative to the main frame, and feeding and guiding mechanism comprising means to move the machine bodily relative to the coal face, and means independent of said moving means to balance the strains produced thereby. 100

8. In a mining machine of the class described, the combination of the main frame, the cutter bar mounted at one end of the frame and adapted to swing from a working position where it projects laterally in one direction from the frame to another position where it projects oppositely from the other side of the frame, the cutting device carried by the said arm, the driver for the cutter device, a motor shaft positioned in the transverse planes of the central part of the frame with its longitudinal axis parallel to the longitudinal lines of the frame and a power transmitting shaft having a horizontal axis parallel to that of said motor 115 shaft and operatively connected to said motor shaft and to said cutter driver. 120

9. In a mining machine of the class described, the combination of an elongated substantially rectangular main frame adapt- 125 130

ed to travel with its side parallel and close to the coal face, a motor on the frame having its armature shaft parallel with the longitudinal lines of the frame, a horizontally arranged cutter chain, an arm carrying said chain and pivotally mounted at one end of said frame on a vertical axis in the central vertical longitudinal plane of the frame, a worm wheel on said axis for driving said cutter chain, a worm actuated by said motor to drive said worm wheel, feed mechanism mounted on the opposite end of the frame, for moving the frame and cutter, comprising a drum, a cable windable on the drum, a worm wheel connectible with the drum, and a worm actuated by said motor to drive the last said worm wheel to wind the cable on the drum. In testimony whereof I affix my signature, in the presence of two witnesses.

NILS D. LEVIN.
